UNITED STATES PATENT OFFICE.

LOUIS DIVEN, OF CYNWYD, PENNSYLVANIA, ASSIGNOR TO THE BABCOCK & WILCOX COMPANY, OF BAYONNE, NEW JERSEY, A CORPORATION OF NEW JERSEY.

BOILER PLATFORM.

Application filed August 4, 1925. Serial No. 48,022.

This invention relates to platforms in connection with boiler furnaces, which platforms may be elevated and lowered in order to give ready access for cleaning or repairing tubes or other parts of the boiler, and will be understood from the description in connection with the accompanying drawings, in which Fig. 1 is a side view of a boiler setting; Fig. 2 is a side view of 5 one of the details showing a track and hoist; Fig. 3 is a side view of a corner of the boiler setting and a platform at the side thereof; Fig. 4 is a plan view corresponding to Fig. 3, and Fig. 5 is a similar 10 view showing a modification, the several views being partly broken away.

In the drawings, the illustrative form of setting has end walls 1 and front and rear walls 1^a. The walls are provided with the 15 usual upright supporting members 2 and stationary walk-ways 3, parallel to the front and rear of the boiler. The walk-ways are provided with the usual hand rails 4 and supports 5. Supports 6 are provided 20 near the upper end of the boiler for transverse I-beam tracks 7 at the front and rear, respectively, of the setting. These tracks extend past the end walls of the boiler setting. If a number of boilers are set in a row, the 25 beams 7 of the several boilers will be positioned end to end to form a continuous track across the entire bank of boilers, in which case, each extreme end of the entire track will be provided with a stop 7^a. Traveling hoists 8, by which the cleaning doors for the tubes which are provided at the 30 front and rear of each boiler may be lifted, run on the tracks 7 and are provided with load-carrying chains 10 with hooks 10^a and 35 operating chains 9 of the well-known type. The elements thus far described are old in boiler constructions.

It has been found, however, especially 40 with boilers of great height, that access to the doors in the side walls of the setting and the ends of the boiler tubes at the front and rear of the setting is difficult and requires considerable trouble. To overcome 45 this difficulty, in the illustrative embodiment, movable platforms are provided which can be operated by the hoists for the cleaning doors and, at the same time, will afford places upon which the workmen may stand for cleaning or repairing the boiler or

tubes. The movable platforms 15 may be 55 made of horizontal channel shaped members 16 that are connected at the corners to form the sides and ends of the platforms. Cross bars 17 to form the floors of the platforms are attached to the lower flanges of the channel members 16, so that ledges will be 60 formed by the remainder of these channels to prevent the escape or accidental falling of tools from the platforms. The platforms are provided with hand rails 18, 65 along one side, that are attached to the platforms in any convenient manner, and brackets 19 are attached to the other side, which brackets carry rollers 20 that are so disposed that they will bear against and 70 roll upon the corner boiler supporting columns 2, as the platforms 15 are raised and lowered, these columns forming tracks for the rollers. Yokes 22 are pivoted to each 75 end of the platforms by passing the lower ends of the yokes through holes in the side channels 16, and these yokes are provided with loops 23 for convenient attachment thereto of hooks 10^a at the ends of the chains 10. Supporting brackets 25 are provided 80 at each end of each setting side wall, these brackets being attached to the columns 2, as shown in Fig. 3.

In the modification shown in Fig. 5, the rollers 20' are disposed within vertically 85 mounted channel irons 27 that are firmly attached to the columns 2, thus preventing the platforms 15 from moving to and fro with respect to the wall, thus guiding the same 90 in a fixed path as they are moved up and down.

The platforms 15 at the sides of the wall rest upon the brackets 25 in their lowermost position, and in such positions they may serve as the usual walk-ways for the 95 sides of the boilers. When walk-ways 3 are provided at the front and rear of the boilers, the auxiliary platforms 15 will rest thereupon in their lowermost positions, but in cases where there are no walk-ways, the 100 movable platforms 15 may serve therefor. In installations where there are a plurality of boilers installed side by side, a single platform 15 at the front or the rear of the boilers of the row will serve for providing access to one end of the boiler tubes of all the 105 boilers, as the platform at the front or rear can be shifted longitudinally along the

tracks 7 to any desired position. The tracks 7 extend beyond the sides of the boiler, so that a hoist 8 at the front and rear of the boiler may be moved to positions where the 5 chains therefrom can be hooked to the yokes 22 of the platform 15 at the side of the boiler, so that a pair of hoists 8 at the rear and a pair at the front of the boiler will serve to elevate and lower a platform at 10 the front and the rear of the boilers, as well as a series of platforms along the side wall of each boiler, in case a plurality of boilers have been installed side by side.

It will be understood that the arrangement 15 described is merely illustrative, and that the embodiment of my invention may be widely varied.

I claim:

1. In combination, a boiler setting, vertically movable platforms at the front and rear ends of said setting, a vertically movable platform at the side of said setting, and traveling hoists for elevating and lowering said platforms, said hoists being movable on supports parallel to opposite walls of the setting and extending beyond the 20 corners of said setting, whereby the same hoists may lift either a platform at the 25

front or rear of the setting and also a platform at the side of the setting.

2. In combination, a boiler setting, a horizontal track disposed on a side of said setting, a hoist running on said track, a platform adapted to be raised and lowered by said hoist, vertical tracks on said setting, 35 and rollers on said platform adapted to engage said tracks and to be guided thereby during movement of the platform.

3. In combination, a boiler setting having two sides intersecting to form a corner, a horizontal track disposed on one of said sides and extending beyond said corner, a platform disposed on each of said sides, and a hoist adapted to run on said track and past 40 said corner, whereby said hoist may be used 45 to raise and lower either of said platforms.

4. In combination, a boiler setting provided with the usual cleaning doors, a track carried by said setting, a hoist running on said track and adapted to raise or lower said 50 doors, a platform adapted to be raised or lowered by said hoist, and means to support said platform when disconnected from said hoist.

LOUIS DIVEN.
